UNITED STATES PATENT OFFICE.

ORRELL ASHTON, OF SWAMPSMOTT, MASSACHUSETTS, ASSIGNOR TO UNITED SHOE MACHINERY COMPANY, OF PATERSON, NEW JERSEY, A CORPORATION OF NEW JERSEY.

GRIPPER.

1,137,566.

Specification of Letters Patent.

Patented Apr. 27, 1915.

Original application filed November 10, 1909, Serial No. 527,210. Divided and this application filed June 25, 1910. Serial No. 568,918.

To all whom it may concern:

Be it known that I, ORRELL ASHTON, a citizen of the United States, residing at Swampscott, in the county of Essex and State of Massachusetts, have invented certain Improvements in Grippers, of which the following description, in connection with the accompanying drawings, is a specification, like reference characters on the drawings indicating like parts in the several figures.

This invention relates to machines for use in working an upper over a last and particularly to gripper mechanism for use in pulling-over and lasting machines.

This present application is a division of an application Serial No. 527,210 filed by me November 10, 1909.

A very important feature of this invention relates to the toe gripping and pulling means. Under the preferred embodiment this feature comprises a toe gripper having sectional jaws which are independently mounted to turn about axes located over the curved corners of the toe, and are also mounted for turning movement together about a central axis. By this arrangement for turning, the toe gripper sections can each be moved or adjusted longitudinally and transversely of the shoe for adaptation to varying shapes and positions of lasts. The grippers are preferably of the curved jaw type and mounted and arranged so that the shoe can be presented with its toe end within and against the inner side of the curved jaws and the jaws thereby adjusted to the shape of each particular last that is presented to the machine. The jaws of the toe gripper are also preferably formed with outwardly inclined gripping faces arranged to take, in its normal, outwardly flared position, the upper of the toe portion of a shoe. A very simple and effective mounting of the toe gripper is provided by which a strong and durable construction is obtained and in these characteristics of the toe grippers are to be found features of this invention.

Another feature of this invention consists in arranging the toe and side grippers for movement together in the direction of the edge of the upper for shifting the upper about the last longitudinally. In the illustrated arrangement the side grippers are

free to move longitudinally of the last and the toe gripper is moved for adjusting the upper edgewise. By this arrangement the entire forward portion of the upper can be adjusted in the direction of its edge around the last by moving the toe gripper, which may be provided with suitable means for that purpose.* The side and toe grippers may be connected to insure edgewise movement together and permit relative upper pulling movements, and means is advantageously provided for reguiding the connected grippers to normal position at the end of each operation of the machine. The described arrangement in which the side grippers are free to move edgewise permits them to respond to the forward pull of the toe gripper which may be applied to draw the upper forwardly on the last. It enables the side grippers to come forwardly with the upper and if a connection between the toe and side grippers is employed the side grippers are compelled to come forwardly with the toe gripper and edgewise straining of the upper between the side and toe grippers, which is the region of the toe tip seam, is avoided.

Figure 1 is a side elevation of the upper pulling and the last resting and depressing means; Fig. 2 is a perspective view of the grippers; Fig. 3 shows one pair of the sectional jaws; Fig. 4 is a bottom view of the toe grippers; Fig. 5 is a detail. Fig. 6 is a section on line 6—6 of Fig. 2.

The machine in its general organization resembles that shown in an application for Letters Patent of the United States. Serial No. 375,669, filed May 25, 1907 by Ronald F. McFeeley.

The side grippers 8 and 9 and the toe gripper are actuated from cams on the main cam shaft, not shown, through yielding connections 11, 12 with the updraw levers 14, 15 from near the front ends of which the grippers are suspended by joints permitting freedom of movement to the grippers. The levers are extended forwardly to provide handles by which the operator can manipulate the grippers to increase or diminish the stretching of the upper or to shift the upper. The toe gripper lever 15 has, in addition to its handle, a lever 16 connected by a slide 17 with the jaw closing mechanism to enable the operator conveniently to

open the jaws of the toe gripper independently of the regular operation of the machine. The toe gripper bar 10 is made cylindrical at its lower end and on it is rotatably mounted a block or carrier 22 having a chamber for a spring 24 and recesses for two rotatable stems 25 on each of which is formed a fixed gripper jaw 26. The movable gripper jaw 28 is pivoted to the outer side of the fixed jaw at 29 and has an eye to embrace the stem 25. The inner side of the eye interlocks with a notched depending extension of a sleeve 30, Fig. 3. The sleeves 30 have notches in their adjacent sides into which fits a disk or plate 32 having a central oblong slot to receive the T-head 33 of the toe gripper closing and uplifting bar and safely interlock therewith when the bar and block 22 are relatively rotated to their normal position. Pins 21 carried on a spring plate 23 extend through the walls of the block 22 into annular grooves in the heads of the stems 25. This connection of the stems with the block 22 and the connection of the sleeves 30 with the bar 10 permits free turning movement of one pair of gripper jaws or gripper section relatively to the other pair or section, so that the two sections can freely conform to the width and shape of the toe portion of the last over which the upper is being pulled. The block 22 is also rotatable upon the bar 10, preferably through a limited angle, so that the gripper sections can not only adjust themselves about the axes of their respective stems, but they can move together about the axis of the bar 10. By these arrangements for turning movements, each gripper section can be displaced, within limits, both longitudinally and transversely of the shoe for adaptation to the shape and position of the last and also for effecting adjustment of the upper upon the last. This latter use is provided for by applying a hand bar 35 to the block 22.

The side grippers 8 and 9, which may be of known construction, are suspended by ball joints from their levers 14 and are guided with the narrow body portion of their blocks 40 within relatively wide ways in the head so that they are free to move with the upper when the upper is adjusted around the toe by the rotation of the toe gripper block 22. This adjustment of the upper by means of the toe gripper, with the side grippers free to move with the upper, is found very satisfactory for tip line positioning. Tip line positioning may involve adjustment of the tip line or seam angularly with relation to the median line of the last and this is effected by the angular movement of the toe gripper by the hand bar 35 as described. Tip positioning also involves adjustment longitudinally of the shoe for obtaining correct and uniform

length of tips. This is obtained in the present machine by manually increasing or diminishing the pull of the toe gripper by the use of the handle on lever 15. By reason of the fact that the illustrated curved toe grippers engage the upper at the sides, as well as at the end of the toe, they do not tend to bow the tip seam and as the side grippers move freely lengthwise of the last they offer no retardation tending to cause the tip seam to be bowed when the upper is pulled upon by the toe gripper.

Very effective stretching of the upper lengthwise of the last, and conformation of the upper to the contour of the heel portion and side faces of the last, is obtained in this machine by the use of the wide curved grippers having engagement with the entire toe portion of the upper at the sides and end so that a lengthwise pulling is effected throughout the breadth of the upper. This thoroughly tensions the vamp and quarter seam along the sides of the last, as well as the side margins of the vamp, without excessively straining the vamp along its median line and at the throat. This result is appreciated in making low cut shoes, the upper edges of which should snugly hug the last and the wearer's foot in order to retain their shape and be comfortable. The freedom of movement of the side grippers of course contributes to this successful use of the toe gripper. It should be noted that the last is held from movement by the sole rest 4 while all the toe and side grippers can be moved together to draw the entire upper forwardly and tighten it about the heel end of the last. The side grippers have on the front and rear faces of their blocks 40 opposed inclines 42 which seat in corresponding inclines in the head when the grippers are restored to shoe receiving position. These inclines regulate the side grippers always to a normal gripping position longitudinally of the shoe, no matter to what position they may have been displaced during the operation on the last shoe.

The bar 35, together with the plate 23, is fastened by a single screw 36, see Fig. 4. By loosening the screw, the plate and the hand bar may be turned to uncover the pins 21 and permit them to be taken out of the stems 25 and, when the block 22 is turned 90° on the bar 10, the two stems and the gripper jaws can be removed. This provision for readily removing one set of jaws and substituting another, enables the machine to be easily provided at all times with grippers having jaws suitable for the work that is in hand, even though the sizes may vary from children's to women's, for example. The plate 23 applies sufficient friction through the pins to the stems 25 to prevent them from undesirable loose move-

ment. It will be noted that the jaws 26 and 28 are so formed and arranged that their gripping faces are at a small angle to the plane of the last bottom by reason of which they are adapted to receive the upper of the forward portion of the shoe in its normal, outwardly flared position. This enables initial folds or puckers in the upper to be avoided and permits the upper to be stretched smoothly over the entire end portion of the last and produce a smooth edged toe, as shown in Fig. 2. The toe and side grippers may, if desired, be connected as shown in Fig. 2, by cylindrical pins 43, 44 arranged to move endwise and turn freely in guideways on the side and front pincers, respectively, and connected together by transverse pins, as shown in dotted lines, Fig. 5, to permit relative angular movement of the toe and side grippers.

In the use of the machine, an assembled shoe, comprising the last, innersole and upper materials is presented to the machine in the relation shown in Figs. 1, 3 and 4. The marginal portion of the upper standing in its normal, outwardly flared position at the toe end of the shoe is readily inserted into the jaws of the toe gripper which are formed to receive the upper without necessarily bending or deflecting it from its normal position. The upper at the sides of the shoe normally stands in a substantially upright position and readily finds its position between the jaws on the side grippers. The bottom rest determines the vertical position of the shoe in the machine and the toe gripper may form the means for positioning the shoe lengthwise and laterally. For this purpose the shoe may be presented with its toe end against and laterally centered in the curved toe grippers. This step of positioning the shoe with relation to the toe grippers has the added advantage that the swinging sections of the grippers are automatically positioned relatively by engagement of the shoe therewith into accordance with the contour of the particular shoe which is to be operated upon. The formation of the inner sides of the gripper sections to facilitate this relative positioning of shoe and toe grippers is well illustrated in Fig. 4. With the work thus presented, the machine is started and caused to close and uplift the grippers for putting the upper under tension and then come to rest. The shoe now stands before the operator in a position inclined forwardly and upwardly so that he can examine the upper and determine what, if any, re-adjustments, additional pulling, and drafting may be required for fitting the shoe properly to the contour of the particular last over which it is being made. If the tip line does not bear the desired angular relation to the length of the last, it is corrected or straightened by

turning the toe gripper by means of the hand bar 35 on the toe gripper block. The side grippers, by reason of the fact that they are free to move forwardly and backwardly, offer substantially no resistance to this tip straightening movement by the toe grippers for they can follow the adjacent edge of the upper in its forward and backward movement. If the toe and side grippers are connected, as shown in Fig. 2, this following of the toe grippers by the side grippers is mechanically insured, and the tip straightening is accomplished by stretching the upper on one side of the shoe between the rear end of the side gripper and the heel and relaxing it on the other side of the shoe. This has the advantage that the upper is not stretched lengthwise or distorted in any way between the toe grippers and the side grippers in the tip straightening operation. Instead thereof, the entire forward portion of the upper from the rear end of one side gripper to the rear end of the other is adjusted edgewise around the last. If the tip line is not in the right longitudinal position, or, as it is expressed, if the tip line is not of the right length, the upper may be pulled farther forward by uplifting the toe gripper by means of the handle on its lever 15. While the side grippers are free to swing forwardly during this forward straining of the upper by the toe gripper, the side grippers may advantageously be depressed to relax the tension on the upper during this forward straining. This can easily be done by the operator grasping the two side levers with his two hands and pulling them downwardly and pressing upwardly with one or both thumbs upon the handle of the toe gripper lever. For this purpose the three gripper levers 14, 15, 14 are arranged close enough together to enable them to be readily grasped as described. If it is desired to adjust the upper transversely of the ball of the last, this is done by uplifting one side gripper and lowering the other, and both side grippers may be uplifted for additionally stretching the upper transversely of the last. If during the inspection and manipulation of the shoe it is discovered that the upper has been pulled too far forwardly, the toe grippers can be caused to release or slacken their hold upon the upper enough to let it slip backwardly and react under its tension. This is done by uplifting the little lever 16 and drawing upwardly upon the block 22 and the gripper stems 25. This has the effect of raising the gripper stems and the gripper jaws 26 with relation to the other jaws and sleeves 30 which are held down by the connection of the sleeve with the bar 10. The incline on the back of the toe gripper bar 10 holds the gripper normally forward at the time of gripping and during the initial pulling so that the stretch-

ing upper is held out of contact with the edge of the innersole to avoid lifting it. As the updraw proceeds, the incline allows the grippers to move inwardly for wrapping the upper over the edge of the shoe bottom so that the grippers may reach a position substantially like that shown in Fig. 1 when the machine stops.

Having explained the nature of this invention and described a preferred construction embodying the same, I claim as new and desire to secure by Letters Patent of the United States:—

1. A pulling-over machine, having in combination with suitable actuating mechanism, a toe gripper comprising sectional jaws mounted for turning movement independently about axes located over the curved corners of the shoe toe and also for movement together about a central axis.

2. In a pulling-over machine, a gripper comprising a stem formed with a jaw having its gripping face oblique to the axis of the stem, a coöperating jaw pivoted at one side of the stem and provided with a closing arm embracing said stem, a sleeve mounted upon said stem and engaging said arm, and means for actuating the sleeve to operate the jaws.

3. In a pulling-over machine, a gripper comprising a block, a stem rotatable in the block and having a jaw, a second jaw pivotally connected to the first, and an operating device for both closing and uplifting the jaws, arranged to permit rotation of the gripper on the axis of the stem.

4. In a pulling-over machine, a gripper bar, a block rotatable thereon, two stems rotatably mounted on opposite sides of the axis of the block, jaws formed on the stems, coöperating jaws pivotally connected with said stems, and means for simultaneously closing said coöperating jaws arranged to permit free rotation of the pairs of jaws independently.

5. In a pulling-over machine, a gripper bar, a block rotatable thereon, two stems rotatably mounted in the block on opposite sides of the axis thereof, jaws formed on the stems, coöperating jaws pivotally connected with said stems, means for simultaneously closing said coöperating jaws arranged to permit rotation of the pairs of jaws independently, and means for turning the block.

6. A pulling-over machine, having in combination with suitable actuating mechanism, a curved toe gripper formed in sections which are freely movable relatively and are arranged to permit the last to be positioned with its toe end within and against the curved gripper and to have its sections positioned relatively in accordance with the shape of the last by such presentation of the shoe.

7. In a machine of the class described, a toe gripper comprising a block or carrier that is rotatable about its longitudinal axis, and pairs of jaws mounted in the carrier for rotation independently about axes located over the curved corners of the shoe toe and at opposite sides of the axis of rotation of the carrier.

8. In a machine of the class described, a toe gripper comprising a carrier, and pairs of gripper jaws mounted for rotation independently of one another about axes located at opposite sides of the center of the toe, said pairs of jaws being adapted to be positioned relatively in accordance with the shape of the toe portion of the last by the presentation of the last against their inner sides.

9. In a machine of the class described, a toe gripper mechanism comprising the two jaws 26 supported for turning movement about parallel axes perpendicular to the plane of the shoe bottom to adapt them to be positioned in accordance with the shape of the toe portion of the last presented in contact with them, and coöperating jaws 28 pivotally connected with the jaws 26 for opening and closing movement and arranged to turn with the jaws 26.

10. In a machine of the class described, a toe gripper mechanism comprising a carrier, two pairs of jaws mounted to turn independently on parallel axes for adapting their relative positions to the curved contour of the toe portion of the last, and one means for restraining both of said pairs of jaws from loose rotation.

11. In a machine of the class described, a toe gripper mechanism comprising a carrier, two pairs of jaws mounted to turn independently on parallel axes for adapting their relative positions to the curved contour of the toe portion of the last presented with its toe end against them, and friction means comprising a spring plate on the carrier and pins forced thereby into position for maintaining the pairs of jaws in the relative position to which they are moved by the last.

12. In a machine of the class described, a toe end gripper mechanism providing a carrier, pairs of gripping jaws mounted in said carrier for turning movement about parallel axes to adapt their position to the width of the last, and means for retaining said pairs of jaws in the carrier constructed and arranged to permit ready removal thereof and the substitution therefor of other pairs of jaws adapted to different shapes of lasts.

13. In a machine of the class described, a toe gripper mechanism comprising a carrier, pairs of gripping jaws mounted in said carrier for turning movement about parallel axes to adapt their position to the width of the last, and an operating bar connected

- with said pairs of jaws and adapted for disconnection therefrom when the carrier and said bar are relatively rotated through 90°.
14. In a machine of the class described, 5 the combination with a carrier, of two pairs of jaws mounted therein and having the operating members 30, the slotted disk 32 engaging both of said members, and the operating bar 10 having the T-head 33 engaging the said slotted disk and adapted for disengagement therefrom when said disk and bar are relatively rotated through 90°.
15. In a machine of the class described, a 10 toe gripper mechanism comprising a carrier, pairs of gripper jaws arranged for free turning movement in the carrier about parallel axes substantially perpendicular to the plane of the shoe bottom, and means for effecting turning movement of the carrier about an axis intermediate the axes of the pairs of jaws whereby said pairs of jaws are relatively moved in opposite directions.
16. In a machine of the class described, a 15 toe gripper mechanism comprising a carrier mounted for turning movement about an axis substantially perpendicular to the plane of the last bottom, and pairs of jaws mounted in said carrier at opposite lateral sides of said axis, said carrier being free 20 to turn about its axis in response to pressure of the shoe against the jaws for adapting the position of the pairs of jaws to the contour of the toe portion of the shoe.
17. In a machine of the class described, a 25 toe gripper mechanism comprising a carrier mounted for turning movement about an axis substantially perpendicular to the plane of the last bottom, pairs of jaws mounted in said carrier at opposite lateral 30 sides of said axis, and means for turning said carrier about said axis whereby one pair of jaws is moved backwardly and the other pair forwardly for shifting the upper at the toe portion of the last.
18. In a machine of the class described, a 35 toe gripper comprising the transversely curved jaw 26 the face of which adjacent to the last is slanted upwardly and outwardly to adapt said jaw to fit the toe end of the 40 last between the last and the upper for seizing short uppers, and the coöperating jaw 28.
19. In a machine of the class described, a 45 toe gripper mechanism comprising relatively movable pairs of jaws arranged to engage an upper at opposite sides of the toe, said pairs of jaws being supported for movement edgewise together for shifting the upper about the end portion of the last.
20. In a machine of the class described, a 50 toe gripper mechanism comprising relatively movable pairs of jaws, and means connected with said pairs of jaws for effecting edgewise movement thereof to shift 55 the upper around the toe portion of the last.
21. In a machine of the class described, an end gripper mechanism comprising connected pairs of jaws for engaging the opposite sides and toe end of a shoe and supported for movement together edgewise about the 60 toe end of the last to position the gripped upper.
22. In a machine of the class described, an end gripper mechanism comprising connected pairs of jaws for engaging the opposite sides and toe end of a shoe, and means for moving said pairs of jaws edgewise about the toe portion of the last.
23. In a machine of the class described, 65 an end gripper mechanism comprising pairs of jaws arranged to engage an upper at the opposite sides and at the toe end of a shoe and connected together to permit relative vertical movement of the side and the toe end jaws and to provide for movement of 70 all of said jaws together edgewise.
24. In a machine of the class described, an end gripper mechanism comprising pairs of jaws arranged to engage an upper at the opposite sides and the toe end of a shoe and 75 connected together to permit free relative in and out movement of said side and end gripper jaws parallel with the plane of the last bottom and to compel movement of 80 said jaws together edgewise.
25. In a machine of the class described, 85 toe grippers comprising a plurality of adjacent pairs of jaws mounted for free turning movement to permit them to adapt their positions relatively to the curved contour of 90 the toe end portion of a last presented against the inner faces of the grippers, and guiding means restraining the grippers from loose forward and backward movement while they are in work receiving position 95 100 whereby they may serve as a positioning abutment for the toe end of the last.
26. In a machine of the class described, 105 toe grippers comprising a plurality of adjacent pairs of jaws mounted for turning 110 movement to permit them to adapt their positions relatively to the contour of the toe portion of a last presented against the inner faces of the grippers, said jaws being formed with outwardly inclined gripping faces extending in a substantially continuous series of connected lines around the toe of 115 the last and arranged to take, in its normal outwardly flared position, the upper of the forward portion of the shoe.
27. In a machine of the class described, 120 grippers for engaging the toe and for engaging the opposite sides of the forepart of the upper of a shoe, means permitting rotation of the toe gripper, and means for moving each of the side grippers independently 125 in directions at right angles to the plane of the last bottom.
28. In a machine of the class described, 130 pairs of toe jaws, means permitting rotation

of said jaws on axes passing therethrough and revolution about an axis lying between them, pairs of jaws for gripping each side of the forepart of an upper, and means for moving all the jaws along the periphery of the last bottom.

29. In a machine of the class described, pairs of toe jaws, means permitting rotation of said jaws on axes passing through them and permitting revolution about an axis lying between them, pairs of jaws for gripping each side of the forepart of an upper, and means for moving all the jaws along the periphery of the last bottom simultaneously.

30. In a machine of the class described, the combination of a gripper mounted for updraw and overdraw movement and composed of a plurality of sections, each section mounted for rotation about an axis passing through the jaws, the gripper as a whole being mounted for revolution about an axis lying between its sections, and side grippers, each having a plurality of sections, adapted to engage the opposite side of the forepart of a shoe upper, said grippers being arranged for updraw movement and for rotation about axes lying between the sections.

31. In a machine of the class described, a sectional toe gripper, the parts thereof being arranged to rotate independently, sectional side grippers for engaging the forepart of a shoe upper, each of said grippers being mounted for rotation about an axis lying between its sections, and means whereby the grippers may be moved along the periphery of the last bottom simultaneously.

32. In a machine of the class described, grippers for engaging the toe and for engaging the opposite sides of the forepart of the upper of a shoe, means permitting rotation of the toe gripper, means for moving each of the side grippers independently in directions at right angles to the plane of the last bottom, and means for moving all of the grippers together in a plane parallel with the last bottom.

33. A pulling-over machine, having in combination, toe gripper mechanism comprising a plurality of pairs of closely adjacent jaws having gripping faces formed and arranged to receive a substantially continuous section of upper extending from one side of the shoe around the toe to the other side in its normal outwardly flared position on the forward portion of the last, means for relatively moving said jaws and the last in a direction substantially perpendicular to the plane of the last bottom for pulling the upper, and side grippers arranged to receive the upper at the sides of the last in its normal upstanding position.

34. A pulling-over machine, having in combination, grippers to engage an upper at the end and opposite sides of the forward portion of a last, and means by which all

said grippers can be moved together in a single operation lengthwise of the portions of the edge of the last adjacent to the grippers.

35. A pulling-over machine, having in combination, grippers to engage an upper at the end and opposite sides of the forward portion of a last, and means connected to one of said grippers by which it can be moved to adjust the upper lengthwise of the adjacent portion of the edge of the last, said other grippers being mounted to move edgewise of the upper with the gripper that is directly actuated.

36. A pulling-over machine, having in combination, toe and side grippers, and actuating means connected with the toe gripper to move it for adjusting the upper edgewise relatively to the last, the side grippers being mounted for free movements edgewise of the upper with the toe gripper.

37. A pulling-over machine, having in combination, toe and side grippers, and actuating means connected with one of said grippers to move it for adjusting the upper edgewise relatively to the last, and connections between said actuated gripper and the other grippers arranged to cause all the grippers to move together.

38. A pulling-over machine, having in combination, toe grippers, side grippers, a connection between the toe grippers and one pair of side grippers arranged to compel them to move edgewise together, and adjusting means for moving said connected grippers.

39. A pulling-over machine, having in combination, toe grippers, side grippers, means connected to the toe grippers to move it for adjusting the upper edgewise about the last, and guiding means for the side grippers arranged to permit them to follow the toe grippers freely in said adjusting movements.

40. A pulling-over machine, having in combination, a toe gripper, side grippers, means whereby said grippers may be moved to adjust the upper edgewise around the toe of the last while all the grippers maintain their hold on the upper, and means associated with the grippers for reguiding all the grippers to normal position after the upper is released.

41. A pulling-over machine, having in combination, toe and side grippers, actuating means for said grippers, and connections between said toe and side grippers arranged to permit the side grippers to be depressed after pulling, and to permit the upper, together with the side grippers, to be drawn toewards by increased pull of the toe grippers.

42. A pulling-over machine, having in combination, a toe gripper, side grippers, and means for actuating the grippers to put

- an upper under tension, said machine having means for permitting the operator to relax the tension on the upper held by the side grippers and pull forwardly the upper, including that held by the side grippers. 5
43. A pulling - over machine, having in combination, a toe gripper, side grippers capable of forward and backward movement together in the same direction, and means 10 for actuating the grippers to put the upper under tension, said actuating means including handled levers arranged in such relation as to permit the operator to depress the side grippers and raise the toe grippers to pull 15 the entire upper forwardly.
44. A pulling - over machine, having in combination, toe and side grippers arranged to seize and pull the upper, and coördinated means for effecting simultaneous adjustment 20 edgewise of the entire marginal portion of the shoe from the rear end of one side gripper around the toe to the rear end of the other side gripper while the toe gripper retains engagement with the toe portion of the 25 upper.
45. A pulling - over machine, having in combination, toe and side grippers arranged to seize and pull the upper, and connections for moving the toe grippers and side grippers together for effecting adjustment of the 30 upper longitudinally around the last.
46. A pulling - over machine, having in combination, toe grippers and side grippers arranged for movement together in the direction 35 of the edge of the upper for shifting the upper longitudinally about the last, and one means for so moving said grippers.
47. A pulling - over machine, having in combination, toe grippers and side grippers 40 arranged for movement together in the direction of the edge of the upper for shifting the upper longitudinally about the last, and connections between the grippers compelling such movements together but permitting 45 relative pulling movements.
48. A pulling - over machine, having in combination, toe grippers and side grippers arranged for movement together in the direction of the edge of the upper for shifting 50 the upper longitudinally about the last, and means for reguiding all of the grippers to normal position at the end of the operation.
49. A pulling - over machine, having in combination, sectional grippers arranged

close together in a curved series around the toe to engage a continuous section of upper extending around the toe end of a last, means for actuating the grippers and last relatively to pull the upper, and means for relatively actuating said grippers and last 60 rotatively to adjust the upper about the last.

50. A pulling - over machine, having in combination, a plurality of grippers for engaging adjacent sections of upper extending around the toe portion of a shoe, and 65 means to simultaneously move said grippers in a direction corresponding substantially with the curved edge of the shoe toe to straighten the toe cap.

51. A pulling - over machine, having in combination, a plurality of grippers for engaging adjacent sections of upper extending around the toe and sides of a shoe, and means to simultaneously move said grippers about a center located back of the toe end of 75 the shoe to shift the upper for straightening the toe cap.

52. A pulling - over machine having, in combination, a plurality of grippers for engaging an upper at the toe end and the sides 80 of the forepart of a last, an opposed rest serving to hold the last against movement while the upper is under tension, means for relatively actuating the last and the grippers to tension the upper upwardly about 85 the forepart of the last, said toe and side grippers being mounted for movement together lengthwise of the last to tension the upper forwardly about the rear part of the last, and means by which the said grippers 90 may be so moved.

53. A pulling - over machine, having in combination, curved grippers located at the corners of the toe of a last and arranged to receive a substantially continuous section of 95 upper extending from one side of the shoe around the toe to the other side in its normal outwardly flared position, and side grippers arranged to receive the upper at the sides of the shoe in its normal outstanding position. 100

In testimony whereof I have signed my name to this specification in the presence of two subscribing witnesses.

ORRELL ASHTON.
